UNITED STATES PATENT OFFICE

ALBERT E. GRANT, OF NEW YORK, N. Y.

ANTISIPHON DEVICE

Application filed September 29, 1927. Serial No. 222,928.

My invention relates to means for preventing liquids from flowing from one point to another by siphoning action.

The object of my invention is to provide simple and efficient means for preventing a liquid such as fuel oil, from flowing from one place to another by siphoning action.

My device is especially useful when installed in oil burning systems where oil is drawn from a source of supply for use as a fuel, to prevent oil from escaping by siphoning action in the event of an open valve or leakage at the point of discharge, after the pump in the system has stopped its operation.

Referring to the drawings which form a part of this specification:

Fig. 1 is a plan view of a construction embodying my invention, hereinafter referred to as an anti-siphoning device.

Fig. 2 is a vertical sectional view of the body portions of my device, and disclosing a helical tube D¹ shown partly in section, inclosed in said body portion.

A, indicates the body portion of my device which is preferably made of suitable metal. The drawing discloses a construction drawn the full size of the device as generally made for use.

B, indicates the inlet and C, the outlet for liquid.

E, indicates a cylindrical chamber having a bore E¹, in which is fitted the lower end of a tube D which closes the bore, and extends downward therefrom into the vertical portion of the conduit F, to a point below the longitudinally extending portion of the conduit F¹.

The upper portion of the tube D is formed in the shape of a helix to provide a long passage-way for the air, which restricts the rapid free flow of air thru the tube while still providing a conduit therethru having an area large enough to pass small particles of solid matter carried in the air, from lodging in the conduit and closing the same, thus rendering the device inoperative.

A small screen G is fitted across the top of the chamber E, and is of smaller mesh than that of the cross sectional area of the conduit, but the aggregate of the opening area thru

the screen being greater than that of the conduit.

It will be seen from the above description that the invention embodies means for providing a long restricted passage of the character described, regardless of the form of its cross section or the specific manner in which it may be constructed, so long as the air is properly restricted in its flow to accomplish its function, whereby valves for this purpose may be dispensed with.

The operation of the device is as follows:

Assuming the inlet B, to be positioned five feet above the oil storage reservoir, and connected therewith by a pipe to lead the oil to the conduit F, and a pipe connected to outlet C, and leading to a pump located on a level below the oil storage reservoir.

The pump when operating, will draw oil from the reservoir thru the conduit F and F¹, and discharge to a burner or other place for use. The pump when first started will draw air thru the screen G and tube D until the oil from the reservoir rises above the lower end of the tube D, and practically closes the passage therethru so long as the oil is flowing upward thru the conduit F, but when the pump stops, and the oil is at rest, air will be drawn thru the tube D, and destroy the vacuum in the conduit F, and the oil therein will flow back into the reservoir, as will be readily understood.

Having thus described my invention I claim as new:

1. An anti-siphon device comprising a body portion having a conduit for liquid formed therein, and having a chamber in open communication with the atmosphere formed therein; and a relatively small helical conduit of restricted area for air supported in said chamber, one end of which extends into said conduit for liquid and the other end of which is permanently in open communication with the atmosphere.

2. An anti-siphon device comprising a body portion having a conduit for liquid formed therein, and having a chamber in open communication with the atmosphere formed therein; and a relatively small conduit for air supported in said chamber, one

end of which extends into said conduit for liquid and the other end of which is in open communication with the atmosphere and a fine mesh screen for filtering the air prior to its passage thru the air conduit, located in the open end of said chamber.

3. An anti-siphon device comprising a body portion having a conduit for liquid formed therein; and a relatively small helical tube for air, one end of which is in open communication with the said conduit in the body portion and the other end in permanent open communication with the atmosphere.

4. An anti-siphon device comprising a body portion having a conduit for liquid formed therein; and a relatively small tube of restricted area formed in a coil to restrict the passage of air therethru, one end of which is in open communication with the said conduit in the body portion and the other end in permanent open communication with the atmosphere.

5. An anti-siphon device comprising a body portion having a conduit for liquid formed therein, and a relatively small helical conduit for air of restricted area, one end of which is in open communication with the conduit for liquid and the other end of which is in permanent open communication with the atmosphere, and a fine mesh screen covering said air conduit, the interstices of which are of less area than that of the air conduit but the combined area of which is greatly in excess thereof.

35 6. An anti-siphon device comprising a body portion having an inlet and an outlet for fluid, a helical conduit for air, the lower end of which is located in said conduit for fluid at a point below the inlet thereto and 40 its opposite end being in permanent open communication with the atmosphere, and a fine mesh screen covering said conduit for air.

In testimony whereof I have affixed my signature.
